LOCK.

1,137,801.

Specification of Letters Patent.

Patented May 4, 1915.

Original application filed July 24, 1911, Serial No. 640,167. Divided and this application filed June 13, 1914. Serial No. 844,997.

To all whom it may concern:

Be it known that I, JOHN H. SHAW, a citizen of the United States, residing in the city and county of New Haven, State of Connecticut, have invented certain Improvements in Locks, of which the following is a full, clear, and exact description.

This invention relates to locks, and more particularly to master-keyed cylinder locks 10 of the type described in my application, Serial No. 640,167, filed July 24, 1911, of which the present application is a division.

One of the objects of the invention is the provision of a cylinder lock having self-contained means, operative by an emergency key, but inoperative by a change key, to actuate by means of a suitable auxiliary or emergency rollback a part of a lock or latch mechanism with which the cylinder lock is 20 associated.

Another object of the invention is to furnish a cylinder lock having a self-contained key-engaging member permanently carried by the lock and so arranged as to be moved 25 relative to the key plug and the regular dog or rollback connected with the key plug, by engagement with the emergency key when the latter is inserted into the keyway, said member when so actuated being adapted to 30 operate a part of the latch or lock mechanism at or about the same time that another part of such latch or lock mechanism is actuated by the regular dog or rollback, said movable member being inoperative, however, to actuate any part of the latch or 35 lock mechanism when a change key is inserted into the keyway.

To these and other ends, the invention consists in the novel features and combinations of parts to be hereinafter described 40 and claimed.

In the accompanying drawing, Figure 1 is a fragmentary vertical section of a mortise lock equipped with my improvements, showing the change key inserted in the cylinder lock. Fig. 2 is a similar view, showing the emergency key inserted into the cylinder lock. Fig. 3 is a rear end elevation of the cylinder lock, and Figs. 4 and 5 are fragmentary elevations of the lock mechanism of 45 the particular mortise lock illustrated, showing the emergency bit or rollback in different positions.

In the particular form of my invention

which I have selected for illustration and description, I provide the cylinder lock with a movable key-engaging member, inoperative by the insertion of a change key, but operative by the insertion of an emergency key, to couple or connect with the key plug 60 of the cylinder lock, a so-called emergency bit or rollback rotatably mounted on the case of the mortise lock. The case 10 of the mortise lock has applied thereto a cylinder lock 11 which comprises a casing or cylinder 65 12, a sleeve 13 rotatable therein, a plug or barrel 14 rotatable in the sleeve, and the usual pin tumblers 15. The key plug carries at its rear end a dog or rollback 16, and the sleeve 13 carries in a similar manner a dog or rollback 17. In the form shown, the movable key-engaging member operative by the emergency key in the manner above stated, is constituted by a swinging device or dog 18, which is adapted to be 70 projected rearwardly of the keyway by the emergency key in order to engage a recess 19 in an emergency rollback 20 rotatable on the wall of the case at a point opposite the cylinder lock. The pivoted member 18 normally hangs in the keyway in the position shown in Fig. 1, substantially within the lines of the cylinder lock. The member 18 operates in a suitable opening in the rollback 16, as shown.

When a change key 21 is inserted into the keyway of the lock the pointed end of the key shank will take into a correspondingly formed recess 22 in the inner edge of the pivoted member 18, and conform to said 90 recess without projecting said member rearwardly. The shank of the emergency key 23, however, is provided with a squared off extremity 23a which does not fit the recess 22, but, on the other hand, comes in full contact with a portion of the edge of the member 18 in such a manner that the latter is thereby projected into a position wherein it extends into the emergency rollback 20 and connects the key plug with said rollback.

The emergency key is usually so bitted as to turn both the key plug and the surrounding sleeve so that it will actuate the rollbacks 16 and 17 together at the same time that it actuates the emergency rollback 20. 105 The change key only turns the key plug and the rollback 16. This is not an essential feature, however, for my improvements are ap-

- plicable to a cylinder lock in which there is no sleeve surrounding the key plug, and in which the cylinder lock carries only one dog or rollback, to wit, a dog or rollback secured 5 to the rear end of the key plug. The rollback operated by the key plug actuates only part of the latch or lock mechanism in the case 10, and the emergency rollback actuates another part of such mechanism.
- 10 When the emergency key is removed from the keyway a spring 25 carried by the emergency rollback 20 within the recess 19 (which spring engages the pivoted member 18 while the emergency key is fully inserted 15 into the keyway) causes said pivoted member to spring back to the initial position in which it disengages the emergency rollback.
- It will be seen from the foregoing description that by my invention I provide an 20 improved cylinder lock construction adapted for use with both a change key and a master or emergency key, wherein a member auxiliary to the usual dog or rollback connected with the rear end of the key plug 25 is carried by the rear end of the cylinder lock and forms a permanent part of such cylinder lock, said member being adapted to be moved relative to the key plug and rollback into an operative position relative 30 to a certain part of the mechanism of a mortise lock when an emergency key is inserted into the keyway, without being so moved when a change key is inserted into the keyway. The auxiliary part or rollback member 18 is adapted to operate one part of the mechanism of a mortise lock, and the dog or rollback 16 is adapted to operate another part of such mechanism. It will be understood also that by my invention the emergency key can, as shown, be substantially of 35 the same overall length as the change key. This dispenses with the use of an extra long emergency key of inconvenient size. Of course, in stating that the emergency key and the change key are of substantially the 40 same overall length, I refer to the shank of the key, *i. e.* that portion which enters the keyway.
- The function of the key-engaging member and its arrangement relative to the regular and emergency rollbacks may be varied 45 considerably.
- Various changes in these and other respects may be adopted within the scope of the invention as defined in the claims.
- What I claim is:
1. A cylinder lock having a key plug, said key plug provided with a keyway, a rollback connected with the rear end of the cylinder lock, 50 means of connection between the key plug and said rollback, whereby the former turns the latter, and a member in said keyway adapted to be moved by a key, operating in an opening in said rollback; substantially 55 as described.
2. A cylinder lock mechanism having two rollbacks, two keys for said mechanism, both adapted to operate one of said rollbacks, and a key-engaging member actuated by one of said keys only for operating the other rollback; substantially as described. 70
3. The combination with a cylinder lock having a key plug and a dog or rollback, of a member at the rear end of said lock forming a permanent part thereof, a key insertible into the key plug, and formed to engage said member and move it relatively to the key plug and rollback, and a second key fully insertible into said key plug without moving said member; substantially as described. 75
4. The combination with a cylinder lock having a key plug and a dog or rollback connected to said key plug, of a movable member permanently connected to and carried by the cylinder lock at the rear end thereof, a key insertible into the key plug to engage said member and move it relatively to the key plug and rollback, a second key insertible into said key plug without moving said member, and means to return 80 said member to its initial position after the first key has been withdrawn from engagement therewith; substantially as described. 85
5. The combination with a cylinder lock having a key plug and a dog or rollback, of a movable member forming a permanent part of said cylinder lock and secured thereto at the rear end thereof, a spring to act on said movable member, a key insertible into said key plug and formed to engage 90 said member and move it in opposition to said spring, and a second key fully insertible into said key plug without moving said member; substantially as described. 95
6. A cylinder lock having a key plug with 105 a keyway, a dog or rollback connected with the rear end of the key plug, a change key insertible into said keyway to rotate said key plug and said rollback, an emergency key insertible into the keyway to rotate said key plug and said rollback, and a member carried by the cylinder lock adapted to be engaged and moved by the emergency key as the latter is inserted into the keyway, said member being immovable by the change key 110 as the latter is inserted into the keyway; substantially as described.
7. A pin tumbler lock having a key plug, said key plug provided with a keyway, a rollback connected with the rear end of said 115 key plug, and a key-engaging member in the keyway projectable rearwardly by a certain key to assume an operative position in respect to a mortise lock mechanism; substantially as described. 120
8. A pin tumbler lock having a key plug, said key plug provided with a keyway, a rollback connected with the rear end of the key plug, a member in said keyway adapted to be moved by a key and operating in an 125 130

opening in said rollback, and a spring for returning said member to its initial position when said key is withdrawn from the key plug; substantially as described.

5 9. A pin tumbler lock having a key plug, said key plug provided with a keyway, a rollback connected with the rear end of the key plug, two keys fitting said keyway, a member movable relative to said rollback and adapted to be shifted relative to said rollback by only one of such keys when the latter is inserted into the keyway, and a spring for holding said member in engagement with the last named key; substantially 10 as described.

10 10. In a pin tumbler lock, a key plug having a keyway, a rollback connected with the rear end of the key plug, a second rollback, and a key-engaging member for actuating 15 the second rollback, movable relative to the first rollback; substantially as described.

15 11. A cylinder lock having a key plug with a keyway, a dog or rollback connected with the rear end of the key plug, a change 20 key insertible into said keyway to rotate the key plug and said rollback, an emergency key insertible into the keyway to rotate the key plug and said rollback, and an auxiliary member projecting into the key- 25 way and adapted to be engaged and operated by the emergency key to actuate a part of a lock or latch mechanism, said member being inoperative by the change key; substantially as described.

30 35 12. A cylinder lock having a casing, a key plug rotatable in said casing and provided with a keyway, pin tumblers in the casing coöperating with the key plug, a rollback connected with the rear end of the key plug 40 for actuating a certain part of the mechanism of a mortise lock, an auxiliary member carried by the cylinder lock at the rear end thereof and forming a part of such cylinder lock, said member being movable relative to said rollback for operating another 45 part of the mechanism of a mortise lock, a change key fully insertible into said keyway to rotate said key plug and rollback without actuating the second named part of the 50 mortise lock mechanism by means of said auxiliary member, and an emergency key insertible into said keyway to rotate said key plug and said rollback, and formed to engage said auxiliary member and move it 55 relative to said rollback into a position wherein it will engage the coöperating part of the lock mechanism; substantially as described.

60 13. A cylinder lock comprising a casing, a key plug therein having a keyway, pin tumblers in said casing coöperating with said key plug, a rollback connected with the rear end of the key plug, an auxiliary member at the rear end of the cylinder lock per- 65 manently carried by said cylinder lock, but

movable relative to the key plug and rollback, a change key fully insertible into the keyway to rotate said key plug and said rollback without moving said auxiliary member relative to said rollback, an emergency key 70 insertible into said keyway to rotate said key plug and said rollback, and having a part at its rear end to engage said auxiliary member and move it relative to said rollback, and means to return said auxiliary member to its initial position when the emergency key is withdrawn from engagement therewith; substantially as described.

75 14. A cylinder lock having a keyway, a key insertible into said keyway, another and 80 different key insertible into said keyway, a rollback carried by said lock and operable by both of said keys, and a member projecting into the rear end of the keyway, and movable rearwardly by engagement with 85 one of said keys, as the latter is inserted into the keyway to actuate said rollback, said member being inoperative by said other key when the latter is inserted into the keyway; 90 substantially as described.

95 15. A cylinder lock having a key plug, said key plug provided with a keyway, a change key insertible into said keyway, an emergency key insertible into said keyway, a rollback operatively connected with said 100 key plug and rotatable by both of said keys, and a member projecting into the rear end of the keyway and movable rearwardly by said emergency key into position to operate a part of a mortise lock mechanism, said member being immovable into operative position by said change key; substantially as described.

105 16. A cylinder lock having a keyway, a rearwardly movable member in the rear portion of said keyway, adapted to operate a part outside of said cylinder lock, a key formed to shift said member rearwardly as the key is inserted into the keyway, another key fully insertible into the keyway without shifting said member, and a rollback on 110 said cylinder lock operable by both of said keys; substantially as described.

115 17. A cylinder lock having two keys, a rollback operable by both of said keys, and a coupling member to operate a part outside of and at the rear of said cylinder lock, operative by one of said keys but not by the other key; substantially as described.

120 18. A cylinder lock having a keyway, two keys insertible into said keyway, said keys being of substantially the same overall length, and an auxiliary member extending into the keyway and adapted to operate a 125 part of a mortise lock mechanism, said member being operative by one of said keys, but not by the other of said keys; substantially as described.

130 19. A cylinder lock having a keyway, a change key insertible into said keyway, an

- emergency key insertible into said keyway and of substantially no greater overall length than said change key, and a member extending into said keyway and adapted to operate a part outside of said cylinder lock, said member being inoperative by said change key but operative by said emergency key; substantially as described.
20. A cylinder lock having a keyway, a key insertible into said keyway, another and different key insertible into said keyway, a rollback carried by said cylinder lock and operative by both of said keys, and a member extending into the keyway and movable rearwardly by one of said keys but not by the other, said keys being of substantially the same overall length; substantially as described.

21. A cylinder lock having a key plug, said key plug provided with a keyway, a sleeve surrounding said key plug, pin tumblers coöperating with said key plug and said sleeve, a key insertible into said keyway to rotate said key plug alone, a second key insertible into said keyway to rotate said key plug and said sleeve together, and a member extending into the keyway and movable into a predetermined operative position by one of said keys but not by the other key; substantially as described.

In witness whereof, I have hereunto set my hand on the 11th day of June, 1914.

JOHN H. SHAW.
